UNITED STATES PATENT OFFICE.

ADDISON BRADFORD, OF BROOKLYN, NEW YORK.

LUBRICATOR.

SPECIFICATION forming part of Letters Patent No. 280,562, dated July 3, 1883.

Application filed December 11, 1882. (No model.)

To all whom it may concern:

Be it known that I, ADDISON BRADFORD, of Brooklyn, in the county of Kings and State of New York, have invented certain new and useful Improvements in Lubricators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to lubricators for journal-bearings, and is particularly applicable to the bearings and journals of car-axles.

Heretofore lubricators for bearings have been made of fibrous materials, saturated with lubricating material, which, after being sometime in contact with the bearing-surfaces, becomes crusty, and fails to supply the proper quantity of lubricant. Distributing-rollers in contact with the journal-bearings have also been employed with more or less merit, but are also more or less objectionable. Some of them fail to supply the lubricant to the journals when it falls below a certain depth in the oil-well. Others are complicated and liable to get out of order. Therefore to overcome and avoid these objections, and to produce a simple, cheap, and effective lubricator, is the object of my invention.

My invention consists in mounting on a simple frame-work a series of loose-fitting rollers in such manner that while the distributing or lubricating rollers are free to yield and adjust themselves to the varying movements of the axle and to the various sizes and constructions of axle-boxes by means of flexible connections, they are at the same time in contact with the dipping or stationary roller which supplies the lubricant, the periphery of the stationary roller being just sufficiently above the bottom of the oil-reservoir to escape contact therewith, so that while there is any oil or lubricant in the oil well or box it is supplied and transmitted to the distributing-rollers, and thence to the journal-bearings.

My invention further consists in the combination, with the frame and lubricating-roller, and coefficient therewith, of means for preventing the waste of the lubricant, which, by

the present constructions, is carried over the oil-box by the axle. By my device this otherwise waste lubricant is caused to drip back into the oil well or reservoir.

55

The accompanying drawings show different means for carrying my invention into effect, in which—

Figure 1 represents a longitudinal vertical section of an ordinary car-axle box or reservoir with my lubricator in position. Fig. 2 represents an end elevation of the lubricator detached. Fig. 3 shows a modification of the same. Fig. 4 illustrates my lubricator and oil-saving device in perspective, and Fig. 5 a modified form of one of my lubricating-rollers.

The same letters denote like parts in all the figures.

A is an ordinary axle-box, and B the car-axle. C is the brass or journal box, and D the bearer. Upon the bottom of the box A is located the frame-work which carries my improved lubricating and oil-saving device, in which E represents the frame; a b, the adjustable or accommodating rollers, supported by arms c d, and held adjustably together by the flexible spring e. These rollers a b are supported and connected to the stationary or laterally-moving roller f, which is in turn supported in journal-bearings in the frame E. The frame E simply rests upon the bottom of axle-box, and incapable of adjusting itself to any variations of the axle.

The spring e may be of any approved shape, form, or style, its object being to hold the distributing-rollers in contact with the journal of the axle, and in such manner as to yield to the irregular up-and-down and lateral movement of the axle. It may be said that the manner of connecting and sustaining the lubricating-rollers upon the supply-roller permits them to have an oscillating and a vibratory movement, so that, no matter what direction the journal of the axle takes, the oil-rollers will be in contact therewith. Should the space between the axle and the bottom of the axle-box be small, the spring will yield sufficiently to permit the oiling-rollers to assume nearly the horizontal plane of the feeding or dipping roller. It will be therefore observed that the rollers never fail to supply the axle-journal with a proper amount of lubricant as long as

any remains in the box or oil-well. As many of these rollers may be used as desired, although one will generally be found ample.

Referring to Fig. 3, which shows a modified form from that of Figs. 2 and 4, the frame is provided with an upwardly-projecting lug, *g*, having a vertical band which is provided with a vertical slot, *h*, in which works vertically the trunnions of a single oil-roller. A corresponding horizontal slot, *g'*, is made in the side of the frame for the reception and working of the trunnion of the supply-roller, and to this trunnion I connect a suitable spring, *k*, which retains the two oil-rollers *i* and *j* in contact.

The operation of this device is: When the axle *B* bears down upon the oiling-roller *i*, the roller *j* yields, which permits roller *i* to slide down automatically, and still be retained in contact both with the supply-roller and with the axle by the tension of the spring *k*.

Any form or design may be employed either for the supply or distributing rollers, one of which is shown at Fig. 5. In this instance the face of the roller is grooved, as seen at *l*. In this groove I place ring *m*, of fibrous or other material—such as leather or rubber—the object being, if found necessary, to inclose the adhesive bearing or frictional contact of the rollers to each other and to the journal.

Fig. 6 shows the oil-saving device attached to the frame of the lubricators, although it may be independent and fixed on a frame of its own. *G* are arms fixed to frame *E* and extending therefrom to near the inner end of the journal-bearing and within the car-axle box *A*.

At the ends of the arms *G* are standards *H*, *H*, at right angles therewith, (or the arms may be bent to right angles,) and upon these standards I locate ordinary spiral or other springs, *I*. These springs sustain a cross-bar, *J*, and upon this bar *J*, I suspend or locate a drip-cloth or other suitable device which will trap or strip the oil from the axle *B* before it reaches outside the box. By this means I accomplish a great saving of oil, that by the old constructions is wasted.

It may be observed that the lubricant is readily carried off by the rapid revolution of the shaft, and, if not arrested, much of it is wasted.

It may also be said that modification, within wide range, of the manner of mounting the oil-rollers may be adopted without departing from the spirit of my invention; hence I do not wish

to confine myself to the exact construction shown.

Having described my invention and the manner of carrying the same into effect, what I claim as new, and desire to secure by Letters Patent, is—

1. The combination, with the axle and axle-box or other journal of a railroad-car, of two or more lubricating-rollers arranged to automatically adjust themselves to the varying conditions of the axle and to the axle-boxes of varying depths when interposed between the axle and box, substantially as described.

2. The combination, with an automatic series of adjusting roller-lubricators, of an axle and axle-box, one or more of said series being in contact with the axle and with a supply roller or rollers, the latter being in a movable frame resting on the bottom of the axle-box, and the former being superposed thereon and attached by yielding or flexible connections, substantially as described.

3. The combination, in a car-axle lubricator, of the frame having fixed supply-rollers, one or more distributing-rollers flexibly connected to the fixed rollers, said rollers and frame being interposed between the axle and box and in contact therewith, and adapted to be adjustable to the varying movements of the axle in either direction, as described.

4. In a car-axle lubricator, the combination of axle *A*, frame *E*, resting on the bottom of said box, rollers *a*, *d*, and *f*, flexibly connected and made adjustable with the axle, as described.

5. The combination, in a car-axle lubricator, of the frame *E*, rollers *a*, *b*, and *f*, connecting rods *c*, *d*, and spring *e*, as set forth.

6. The combination, with an automatically-adjustable lubricating-roller, of the frame *E* and oil-saving device *F*, the latter being adjustable to the axle and adapted to be carried by the frame longitudinally, as shown and described.

7. The combination, with an axle-lubricator, of the oil-saving device, consisting of arms *B*, standards *H*, springs *I*, cross-head *J*, and scraper *F*, with the axle, as set forth.

In testimony that I claim the foregoing as my own I hereunto affix my signature in presence of two witnesses.

ADDISON BRADFORD.
